WESTERN UNDERWOOD, OF SANTA MONICA, CALIFORNIA, ASSIGNOR TO LA LUX MANUFACTURING COMPANY, OF LOS ANGELES, CALIFORNIA, A CORPORATION OF CALIFORNIA

CORE FOR MOLDS

Original application filed December 14, 1927, Serial No. 239,915. Divided and this application filed March 22, 1930. Serial No. 437,995.

This invention has to do with an insert for a mold and has particular reference to an insert for a post or column mold.

Elongated monolithic or cementitious objects, such, for example, as columns or posts, are usually cast or formed in suitable molds and in accordance with various processes of manufacture the molds are operated in various ways to obtain the desired packing of the material. In certain cases, for instance, in the case of a post to be used in a lighting standard or electrolier, it is desirable to provide a longitudinal opening through the cast body and it is ordinarily necessary to provide a metal reinforcing structure in the cast body. In practice difficulty has been experienced in obtaining the desired opening through a post or column and also in forming a post with a metal reinforcement under proper conditions of strain and in the proper position in the cast body.

This application is filed as a division of my co-pending application entitled Insert for molds, Serial Number 239,915, filed December 14, 1927.

It is an object of this invention to provide an insert for a mold, for instance, a post mold, whereby the desired opening is cast or formed accurately in the finished product.

Another object of this invention is to provide an improved, simple, and practical form of core and core carrier for use in connection with a post mold, or the like.

The various objects and features of this invention will be best and more fully understood from the following detailed description of a typical form and application of the invention, throughout which description reference is had to the accompanying drawings, in which:

Fig. 1 is a longitudinal detailed sectional view of a post mold showing the insert provided by this invention in place therein. Fig. 2 is a view of the base end portion of the insert shown independent of the mold. Fig. 3 is a view taken as indicated by line 3-3 on Fig. 2 showing the formation of the core carrier provided by my invention. Fig. 4 is an enlarged transverse sectional view

taken as indicated by line 4-4 on Fig. 1, being a view showing in detail the spacer provided by my invention, and Fig. 5 is a sectional view taken as indicated by line 5-5 on Fig. 4.

The insert or core provided by this invention is intended primarily for use in a mold, such, for instance, as a post mold, or the like. For purpose of example I will refer to the core as applied to a post mold of the construction set forth and claimed in Patent Number 1,700,522, entitled Mold construction, issued to me January 29, 1929. This particular mold includes an elongated sectional body 10 having an opening A designed or shaped to give the post the desired external configuration. The body 10 is different at its two ends, one end being comparatively large to form the base portion of the post, the other end being small and adapted to form the head end of the post. The head end of the body 10 is closed by a cover plate 11 over which is applied a mounting plate 12, while the base end of the body is closed by the core carrier 12^a provided by this invention and a mounting plate 13 applied over the core carrier.

The insert provided to go into the mold includes, generally, an elongated core 14 to be arranged longitudinally through the opening A in the body, the core carrier 12^a which is applied to the base end of the body and supports the core 14, a reinforcement 15 for arrangement in the space A to be cast in the post, and a spacer 16 operable to definitely space the reinforcement in the post. The core 14 and core carrier 12^a are the general subject matter to which this application is directed, the reinforcement 15 and spacer 16 being set forth and claimed in my co-pending application entitled Insert for mold, Serial Number 239,915, filed December 14, 1927.

The core 14 is shaped and proportioned to form the desired opening in the cast structure or post, and in the case of a post for the usual form of lighting standard, the core is provided with an enlarged base part 20 which forms a comparatively large chamber in the base portion of the post, and an elongated

gated body part 21 which is slightly tapered and extends from the base part 20 to the head end of the mold. The body part 21 of the core has its large end adjoining the base 20 and the base is provided with a taper or draft allowing the core to be withdrawn from the molded post from the base end. In the preferred construction the core is formed of metal, for instance, sheet metal, and in this case the core parts are hollow. In accordance with my invention, a plug 22 closes the small or outer end portion of the core body 21 as shown in the drawing. The plug is preferably somewhat removed from the end of the body so that a socket B is formed in the end of the core body to receive a guide part on the mold cover 11 and/or various tools or devices as set forth in the above-mentioned patent granted to me on mold construction. The plug is fixed in the core body so that it can be engaged in driving or forcing the core out of the casting. In Fig. 1 of the drawing the core is shown in position where a projection on the cover 11 extends into the socket B to hold the core body in position in the opening A.

The core carrier 12^a provided by this invention is preferably in the form of a flat plate adapted to be attached to the base end 30 of the mold body 10, as shown in Fig. 1. The carrier 12^a is adapted to be mounted in a definite position on the base through bolts 25, or the like. In accordance with this invention the base portion 20 of the core is attached to the carrier 12^a, preferably permanently attached. My invention provides one or more openings 26 in the core carrying plate 12^a through which the material to be cast can be filled into the mold. In the drawing I have shown a construction wherein there are several openings 26 which communicate with the opening A in the body of the mold when the core carrier 12 is in place, as shown in Fig. 1. Further, the opening or openings 26 in the core carrier are located to be closed by the mounting plate 13 upon the mounting plate being arranged in place, as shown in Fig. 1.

The core structure provided by my invention is not only a particularly simple and inexpensive structure, but is also very convenient to handle. It is to be noted that the core, when in place, is effectively supported at both ends so that it is positively held in a predetermined position in the space A in the mold body. Further, as above pointed out, my construction allows the mold to be filled with the core set in position and permits of the core being withdrawn from the cast body without disturbing the casting in the mold body 10.

The reinforcement 15 provided by my invention includes, generally, a plurality of longitudinal rods 28, foot brackets 29 on the lower or base ends of the rods, and one or

more transverse ties 30 extending between the rods. The rods 28 may be formed of suitable reinforcing bars such as are used in reinforcing concrete structures, and the like, it being preferred to use twisted, square bars or the equivalent. In practice I may use any desired number of bars 28, it being understood that the number and weight of bars will depend upon the character of reinforcement desired. The foot brackets 29 are fixed, for instance, welded, or otherwise positively secured to the base ends of the rods 28, and are formed to have projecting parts 31 adapted to be attached to the base end of the mold body 10. The upper or head ends of the bars 28 preferably project from the finished post and therefore are proportioned to project into suitable sockets or openings provided in the cover plate 11 of the mold body. My construction is such that the head ends of the rods 28 do not have to be made tight in the cover 11 of the mold, in fact, it is preferred that they be allowed to extend freely into the openings of the cover 11 so that the cover merely operates to space them apart and not hold them longitudinally. The transverse tie or ties 30 may be in the nature of wires wound around the several rods 28 in a manner such as I have illustrated in the drawing. The tie 30, when properly applied to the rods 28, ties them in or together so that they have little or no tendency to expand or move out radially in the event the mold structure in which the reinforcement is spaced is rotated in the course of manufacture of the post.

The spacer 16 provided by my invention is in the nature of a ring or annular member adapted to engage the several rods 28 and to surround the body 21 of the core so that it operates to definitely hold and space the rods 28 with reference to the core and therefore in the space A of the mold body 10. My invention provides a ring 32 adapted to fit around the core body 21 with substantial clearance and made comparatively narrow or thin so that it occupies comparatively little space in a radial direction in the mold space A. In accordance with my invention the ring 32 is provided with a plurality of inwardly extending lugs 33 adapted to engage the core body 21 so that the ring 32 is definitely, for instance, concentrically, related to the core body. Further, my invention provides a plurality of outwardly projecting lugs 34 on the ring 32, the lugs 34 being provided to hold the bars 28 of the reinforcement. In the preferred construction the lugs or projections 34 are provided with openings to pass the bars 28, as clearly shown in Fig. 4 of the drawing. In the drawing I have disclosed an arrangement wherein there is a single spacing ring embodied in the structure or mold insert. It is to be understood, however, that any de-

sired number of spacing rings may be provided as circumstances may require.

From the foregoing description it will be apparent that my invention provides a structure or combination of parts for insertion of a mold body whereby the cast structure is cored to have an opening in a definite position, and whereby a suitable reinforcing structure is embodied in the casting in a definite position without requiring tensioning or other straining, such as is liable to interfere with the proper bond between the reinforcement and cast material.

Having described only a typical preferred form of my invention, I do not wish to limit myself to the specific details set forth, but wish to reserve to myself any changes or variations that may appear to those skilled in the art or fall within the scope of the following claims.

Having described my invention, I claim:

1. In combination, a tubular rotary post mold, an insert for the mold including a plate for attachment to one end of the mold, and a unitary tubular core fixed to the plate to project through the mold to its other end, the plate projecting radially beyond the core to contact with an end of the mold and having an opening in the projecting part to admit material into the mold and a mounting member to connect said end of the mold with a rotating device, said member closing said opening.

2. In combination, a rotary post mold having a guide part at one end, an insert for the mold including a plate for attachment to one end of the mold, a unitary tubular core fixed to the plate to project through the mold to its other end, and a plug in the core and spaced from the end of the core at said other end of the mold forming a socket in the end of the core to receive said guide part, the plate projecting radially beyond the core to connect with the mold and having an opening in the projecting part to admit material into the mold, and a member for mounting the mold on a rotating device adapted to be attached to the mold and close said opening in the plate.

50 In witness that I claim the foregoing I have hereunto subscribed my name this 29th day of November, 1929.

WESTERN UNDERWOOD.
